UNITED STATES PATENT OFFICE

THEODORE L. SMITH, OF CONCORD, MASSACHUSETTS, ASSIGNOR TO GILLETTE SAFETY RAZOR COMPANY, OF BOSTON, MASSACHUSETTS, A CORPORATION OF DELAWARE

SAFETY RAZOR

Application filed November 18, 1930. Serial No. 496,446.

This invention relates to safety razors of the type wherein a thin and usually flexible blade is supported and clamped in shaving position between cap and guard members.

- 5 This clamping has heretofore been done by means of the razor handle which is screw threaded to a stud on the razor cap and any releasing adjustment of the handle has permitted a looseness at its connection with the 55
 10 razor. Such adjustment is frequently made for various purposes as hereinafter pointed out and it is the primary object of my invention to provide a construction wherein the clamping means can be adjusted or released to any desired position without affecting 60
 15 the connection between the handle and razor.

When a razor of the above defined type is clamped to its maximum position of tightness, the cutting edges of the blade are brought to a position most closely adjacent to the guard and these edges in this position have the least amount of cutting exposure. Releasing of the clamping action against the 25 blade permits the blade edges to move slightly away from the guard and thereby increase this cutting exposure. In accordance with my invention, the clamping action may be released to thus increase the blade edge exposure without objectionably affecting the 30 security and rigidity of the connection between the razor and its handle. The razor is, therefore, held firmly and securely on the handle regardless of the position of this 35 blade edge exposure adjustment.

Among other improved features in the new Gillette razor is a rust-proof blade which needs only to be rinsed after shaving, thus eliminating the blade removing and drying 40 operation heretofore necessary. When this blade is to be rinsed, the razor parts are released from their shaving position sufficiently to permit the flexed blade to return to its normal flat condition to thereby become 45 spaced from the guard and to permit free passage of a stream of rinsing water.

50 My invention is particularly applicable to the well-known Gillette type safety razor in which the blade is clamped between cap and guard members and in such an assembly it

is now proposed to provide independently acting means cooperating with the members for retaining them in their assembled relation while permitting release of the clamping means and separation of the members to 55 the blade cleansing position, the said retaining means being independently releasable for the purpose of removing and changing blades. In the preferred form of the invention the assembly retaining means and 60 the blade clamping means are formed as parts of the razor handle and preferably on relatively telescoping parts thereof, rotation of one of said parts being adapted to clamp the blade for shaving or release the blade for 65 cleansing and rotation of the other part being adapted to disassemble the razor. In one respect my invention consists in an improved razor having these novel and useful characteristics. 70

75 My invention furthermore contemplates an improved safety razor of the above defined type wherein the outer and blade clamping and releasing element of the handle is swivelled to the razor guard whereby, upon being released, it not only permits separation of the cap and guard but positively withdraws the guard from the cap. My improved razor also preferably employs two independent means, as screw threads, on the 80 cap stem for engagement by the two handle elements, such construction permitting the adjustment or release of one of said elements without affecting the other element or its connection to the razor. 85

In the accompanying drawing I have shown certain specific embodiments of my invention but it will be understood that the invention can be otherwise embodied and that the drawing is not to be construed as defining or limiting the scope of the invention, the claims appended hereto being relied upon for that purpose. 90

95 Referring to the figures of the drawing,

Fig. 1 is a perspective view of a razor embodying my invention;

Fig. 2 is a longitudinal sectional view through one form of my razor and showing the same in clamped shaving position;

100 Fig. 3 is a fragmentary view like Fig. 2

but showing the parts released for rinsing;

Fig. 4 is a longitudinal sectional view through a modified form of my razor; and

Fig. 5 is a like view illustrating a further modified construction.

The form of my invention illustrated in Figs. 2 and 3 will be first described. This razor comprises a cap 10, a guard 12, a blade 14 therebetween, and a handle composed of two elements 16 and 18. The cap and guard are relatively located by means of a centrally disposed rib 19 on the inner face of the cap cooperating with and extending into a groove 21 in the guard. The blade is located by means of a centrally disposed slot which fits over this rib of the cap. The blade is flexible and normally flat, as in Fig. 3, and the adjacent faces of the cap and guard are of such contour as to flex the blade to the transverse curved position shown in Fig. 2 when the cap and guard are clamped together on the blade. Extending outwardly from the blade engaging face of the cap is a stem having two relatively spaced screw threads 20 and 22 thereon. A portion of the handle element 18 is telescoped within the handle element 16 and the inner ends of these elements are threaded to respectively engage the cap stem threads 20 and 22.

The outer handle element 16 comprises a relatively long sleeve having a solid portion 24 pressed into its inner end, the inner end of this portion being threaded to receive the cap stem thread 20 and the remaining portion thereof having a bore 26 therethrough for receiving and supporting the reduced inner end 28 of the inner handle element 18 when the thread engagement is released, as in Fig. 3. The inner end of the outer element 16 is knurled and is preferably of a size substantially corresponding to the sleeve. Intermediate this knurled end and the reduced portion 28 is a stepped portion 30 on which is supported the outer end of the sleeve 16. This outer handle element is thereby rotatably supported on the inner element, sufficient clearance, however, being provided between the portions 28 and 24 to permit the portion 28 to freely engage its screw threads 22 on the cap stem. I also preferably swivel the inner end of the outer handle element to the guard and this may be conveniently done by forming an extended portion on the inner end of the part 24, assembling the same within the smaller end of a stepped hole in the guard and bending the portion over at 32 before internally threading the part 24. The outer handle element is thereby closely but rotatably connected to the guard by the interengaging annular portions 32 and 34.

The function of a razor thus constructed may be briefly described as follows. In assembling the razor parts, the blade is placed on the cap and the guard on the blade in the usual and well-known manner. The inner

handle element 18 is then inserted into the outer handle element and threaded tightly to the cap stem thread 22, that is, turned until stopped by the end of the thread so that the cap and the inner handle member 28 constitutes a rigid assembly. The razor parts are thereby connected together and can be disassembled only by releasing this thread connection at 22. To clamp the blade between the cap and guard it is only necessary to engage the outer handle element with the thread 20 and tighten the same, this position of the parts being shown in Fig. 2. If it is desired to secure a slightly greater blade edge exposure, the outer handle element is slightly unscrewed whereby the blade edges will move away from the guard, as illustrated in Fig. 4, and hereinafter described. It will be observed that this releasing action in no manner affects the connection of the inner handle member 28 with the cap stem at 22 and since the outer element is rotatably supported at 20 and 30, the handle remains firmly and securely engaged with the cap. When it is desired to rinse the blade and razor, the outer handle element is fully released, as shown in Fig. 3, whereupon the blade straightens to its flat shape and becomes spaced from the guard. It will be noted that in this condition of the razor, the guard is released from its engagement with the rib 19 and is free to spin with the sleeve member 16 upon the inner handle member to which the cap remains firmly secure.

The form of my invention shown in Fig. 4 differs from that just described in that the outer handle element is not swivelled to the guard but the two handle elements are swivelly connected together. This razor comprises a cap 40, a guard 42, a blade 44, and a handle comprising outer element 46 and inner element 48. The cap stem has relatively spaced inner and outer threaded portions 50 and 52 and, as in Fig. 2, the outer portion 52 is of a smaller diameter. The reduced portion 54 of the inner handle element extends into the outer element and is threaded to the cap stem at 52. The outer element is adapted to thread onto the cap stem at 50 and bears directly against the guard.

In the form of my invention shown in Fig. 2, only the inner handle element 18 is removable from the cap and guard. In the Fig. 4 form of the invention, both handle elements are removable but may not be disassembled one from the other. This relation is provided by means of a pin 56, sent into the portion 54 and a bushing 58 pressed into the outer end of the element 46. In assembling the parts, the bushing is first placed on the reduced portion 54 and against the knurled portion 48 and the pin or lug 56 is then secured to the portion 54. The parts are thereafter assembled, as shown in Fig. 4, by forcing the bushing in

place through the medium of the knurled head 48.

The operation of this form of the invention is substantially the same as that of Figs. 2 and 3. The parts are secured together by the thread engagement at 52 and tightening of the outer element 46 onto its thread 50 serves to clamp the blade in shaving position. The position of the blade when fully clamped is shown in broken lines in Fig. 4. When the element 46 is slightly released, the blade moves toward its plane shape whereby its cutting edges are further spaced from the guard, as shown in full lines, these edges thereby being further exposed for shaving. The blade may in like manner be fully released to the rinsing position corresponding to Fig. 3 and in such position the threaded portion of the element 46 is between the threads 50 and 52 and the cap, guard and blade are freely rotatable relative to the main exterior handle portion 46.

The construction of Fig. 5 is similar to that of Fig. 4. In this razor the two relatively spaced threaded portions 60 and 62 on the cap stem are of the same diameter and are respectively engaged by the outer and inner handle elements 64 and 66. The construction of the element 66 is similar to that of Fig. 2, i. e., comprises an outer knurled head 66, an inner reduced portion 68, and an intermediate stepped portion 70. The portion 70 may be relatively long whereby to provide a firm bearing for the outer sleeve 64. The two handle elements are also connected together by a pin 72 and a bushing 74 assembled and functioning like those of Fig. 4 and above described. The operation of this razor is substantially the same as above defined and further description thereof is, therefore, believed to be unnecessary.

Having thus described my invention, what I claim as new and desire to secure by Letters Patent is:

1. A safety razor comprising cap and guard members for gripping a blade and holding it in position for shaving, a stem on the cap having axially spaced threads, a handle member connected to the stem at one thread, and means also connected to the stem at its other thread and rotatable in opposite directions to respectively force the cap and guard into blade clamping relation and release their clamping action on the blade, the said means being swivelled to the guard member and being operative while the thread connection between the handle member and stem remains secure.

2. A safety razor comprising cap and guard members for gripping a blade and holding it in position for shaving, a stem on the cap having spaced thread portions, a handle member threaded to one portion of the stem, and means threaded to another portion of the stem and rotatable in opposite directions to respectively force the cap and

guard into blade clamping relation and release their clamping action on the blade, co-acting means on said handle and stem to maintain the threaded portion of the handle and the other threaded means in spaced relation, the said two stem portions being of the same diameter and the said means being operative while the thread connection between the handle member and stem remains in fully tightened condition.

3. A safety razor comprising cap and guard members for gripping a blade and holding it in position for shaving, a stem on the cap, a handle member threaded to an outer portion of the stem, and means threaded to an inner portion of the stem and rotatable in opposite directions to respectively force the cap and guard into blade clamping relation and release their clamping action on the blade, the said outer portion of the stem being of smaller diameter than the said inner portion and spaced therefrom and the said means being operative while the thread connection between the handle member and stem remains in fully tightened condition.

4. A safety razor comprising cap and guard members for gripping a blade and holding it in position for shaving, a stem on the cap, a handle member including a relatively long sleeve with a portion at one end threaded to the stem and adapted to force the cap and guard into blade clamping relation, and a cooperating handle member extending through the sleeve and threaded to the stem in spaced relation to the threaded connection of the stem and sleeve, and means to prevent locking engagement between the threaded end of the sleeve and the threaded handle member.

5. A safety razor comprising cap and guard members for gripping a blade and holding it in position for shaving, a stem on the cap, a handle member including a relatively long sleeve with a portion at one end threaded to the stem and adapted to force the cap and guard into blade clamping relation, a cooperating handle member having a reduced inner portion extending through the sleeve and independently threaded to the stem, means holding the said reduced inner portion centered within the sleeve, and means preventing separation of the two handle members.

6. A safety razor comprising cooperating cap and guard members, the cap having a stem with two axially spaced threads thereon, an elongated handle member adapted to be screwed firmly upon the endmost thread of the cap stem and to maintain secure connection therewith, and a sleeve member enclosing said handle member and adapted to be screwed on or unscrewed from the innermost thread of the cap stem leaving said elongated member in fixed position.

7. A safety razor comprising a cap having

- a blade locating rib and a stem with spaced threads thereon, a guard recessed to receive said stem and having a groove to receive said rib, a slotted blade positioned by said rib, an inner handle member connected to the stem 5 at its outermost thread, and a sleeve rotatable thereon and connected to the stem at its innermost thread, means to prevent locking engagement between the threaded handle member and the threaded portion of the sleeve 10 and means to maintain said cap, guard and blade in spaced relation for cleansing purposes.
8. A safety razor comprising a cap having a blade locating rib and a stem with two threads thereon spaced apart a distance substantially as great as the height of the rib and a guard recessed to receive said stem freely and having a groove corresponding to 20 said rib, an inner member connected to the stem at its outer thread, and an outer handle member connected to the stem at its innermost thread and having also a connection with the guard whereby the guard may be moved to a position clear of the rib independently of the connection between the handle member and the stem.
9. A safety razor comprising a cap having a stem threaded at separate points, a guard 30 loose upon said stem, a tubular handle member threaded upon the stem adjacent to the guard and an inner handle member constructed and arranged for independent threaded engagement with the stem and connected to said tubular member for limited longitudinal movement with respect thereto.
10. A safety razor comprising cap and guard members for gripping a blade and holding it in position for shaving, a handle 40 including two elements disposed in telescopic relation, a stem on the cap member, said stem being threaded and said elements having threaded portions, both of said elements adapted to engage the threaded stem simultaneously, co-acting means on said stem and inner telescopic element to prevent locking engagement of said elements when threaded on said stem, means to maintain the cap and guard in spaced relation for cleansing purposes when the outer telescopic element is unthreaded from the stem.
11. A safety razor comprising cap and guard members for gripping a blade and holding it in position for shaving, a handle 50 including two elements disposed in telescopic relation, a stem on the cap member, means on adjacent ends of said elements to co-act with means on said stem to maintain the members either in gripping relation on a blade or in loosely spaced relation from each other, co-acting stop means on said stem and inner element to maintain the adjacent ends of said handle elements in spaced relation.
12. In a safety razor comprising cap and 60 guard members for gripping a blade and holding it in position for shaving, said cap having a threaded stem, a handle including handle elements, the adjacent ends of said elements being threaded and adapted to engage the threaded stem simultaneously, means to maintain the threaded ends of the handle elements in spaced relation, means to maintain the guard, cap and blade in spaced relation for cleansing purposes when one of the handle elements is unthreaded from the stem.
13. In a safety razor comprising cap and guard members for gripping a blade and holding it in position for shaving, said cap having a threaded stem, a handle including handle elements arranged in telescopic relation, the adjacent ends of said handle elements being threaded to engage the threaded stem at different points respectively, the stem being shaped to maintain the threaded ends of the handle elements in longitudinally spaced relation when so engaged, means to maintain the cap, guard and blade in spaced relation for cleansing purposes when one of the handle elements is unthreaded from the stem.
14. A safety razor comprising cap, guard and blade including a handle therefor, said cap having a threaded stem extending through the blade and guard and into the end of the handle, said handle including handle elements which are threaded at their adjacent ends to engage the threaded stem, means incorporated in the handle structure to maintain the threaded handle element ends in spaced relation, means on the stem providing for limited separation of cap, guard and blade for cleansing purposes, co-acting means on handle and stem to prevent the accidental separation of the cap from the remainder of the razor, and co-acting means on cap, guard and blade to maintain alignment of cap, guard and blade even though the cap, guard and blade are in position of limited separation.
